BUTTON OR BUTTONHOLE GAUGE

Lou Swartz, Brookline, Mass.

Application May 3, 1948, Serial No. 24,715

6 Claims. (Cl. 112—75)

1

The invention herein described relates to an apparatus for spacing buttonholes and buttons on garments. More particularly, the present invention involves a carriage, designed to operate as an adjunct to a conventional buttonhole cutting or button sewing machine by carrying a garment or material upon which buttonholes are to be made or to which buttons are to be affixed, and which will automatically space the buttonholes or buttons by a predetermined distance.

The object of this invention is to provide a means whereby a garment or material, upon which it is desired to make buttonholes or attach buttons, may be fed to the conventional buttonholing or button sewing machine so that the desired points of operation on the garment will be automatically positioned for the operation of the machine.

At present the common mode of performing these operations is by hand, whereby the locality for each button or buttonhole is marked by hand and then the garment is positioned by hand for each operation of the machine. The advantages obtained from this apparatus are greater accuracy, faster operation, and less manual skill and labor in the positioning of buttonholes or buttons than has heretofore been possible.

Generally this apparatus designed to operate as an adjunct to a conventional button sewing or buttonhole cutting machine, consists of a garment carrying element preferably in the form of a plate having a cut away portion, but may be of any construction which will afford a unitary pair of oppositely disposed coplanar sections having an opening therebetween, having wheels which move along a fixed race guide, or track on the machine bench. The garment upon which the operations are to be performed is positioned and clamped on the carrying plate so that the area on which the operations are to be performed is located over the opening or cut away area. As the plate is moved along the race, the desired area of the garment passes the operating position of the machine. To fix the position and spacing of the buttons or holes, adjustable stops are located along the race assembly which engage a catch located on the plate, so that as the desired area of the garment passes through the operating position of the machine, the plate will be stopped at each point where a button is to be affixed or a hole made. At each stop the operation of the machine is performed and the plate is then moved to the next stop.

Thus, after properly positioning the garment on the plate and spacing the adjustable stops,

the operator need only move the plate from stop to stop to effectuate a proper and accurate locating of the point of the garment upon which the machine is to operate.

In describing the apparatus of this invention in detail, reference will be had to the accompanying drawings wherein Fig. 1 is a top view of the plate, Fig. 2 is a cross sectional view of the plate and its race taken along the line 2—2 of Fig. 1, and Fig. 3 is a cross sectional view of the plate and the race assembly taken along the line 3—3 of Fig. 1. Fig. 4 is a detailed view partly in section primarily to show the stop mechanism. Fig. 5 is a plan view of one of the stops.

15 The plate 10, constructed of suitable structural and supporting material such as wood or sheet metal, which, as can be seen from Fig. 1, is preferably rectangular in shape but having a relatively large portion cut away forming an operating area 11. A plurality of paired and parallel elongated slots 13 are designed to receive clamps 12 in transverse adjustability to the race, two clamps being shown in Fig. 1 positioned in their respective pairs of slots located on opposite sides 20 of area 11. The adjustability of these clamps is perpendicular to the line of travel of the plate along the race, the race assembly being described in detail below. Clamps 12 are preferably of the spring type and each have a guide flange 30.

25 Attached to the buttonholing or button sewing machine bench 17 is a bench extension 14 upon which is fixed a race assembly 15 forming the race, guide, or track 16, as shown in Fig. 2.

30 Secured to the plate 10 and depending therefrom are a plurality of legs 18 to which are secured wheels 19. These legs and their corresponding wheels are arranged in two parallel rows or sets, one set riding upon the bench 17 and the other riding in race 16 and guided thereby 35 as shown by Figs. 2 and 3.

35 Located on and along the race assembly 15 are a plurality of adjustable stops 20. Their adjustability lies along a line parallel to the race 16 and may be effectuated by any conventional 40 means such as by an elongated slot or slots running parallel to the race in which these stops may slide and be clamped in adjusted positions, or by closely spaced oblong holes 31 running parallel to the race into which these stops may 45 be snugly fitted.

Attached to and depending from the plate 10 is the catch 21 which is designed and positioned to engage the stops 20 as plate 10 is moved along the path of race 16.

50 The stop and catch arrangement may be of

any suitable conventional type wherein the catch will be held in fixed position when engaging the stop, but will be released when increased force is exerted in the direction of travel. The particular stop and catch arrangement shown in Figs. 2 and 3 consists of a stop having a recess 25 on its catch engaging face and a yieldable catch whose stop engaging portion is shaped to fit into the recess 25. The engaging surfaces are of such complementary shape and slope that, as the catch 21 engages stop 20, its hollow engaging element 22 will ride upwardly on rod 23 against the force of spring 24 until the catch is over the recess 25 of the stop, when the spring forces the engaging surface of the catch to enter the recess. The catch will then be held in position until increased force is exerted in either direction along the race so as to cause the catch and stop to disengage.

This automatic button or buttonhole spacing apparatus is designed to work in conjunction with the conventional button sewing or button-hole cutting machine. The plates 10 and 14 are mounted on the bench or work table 17 of the machine so that cut out area 11 may be moved into suitable spatial relationship with the operating head 50 of the machine to effect the above described object of the apparatus. When a suitable position for the plate has been determined, a race assembly such as 15 is affixed to the bench either directly or by means of a bench extension to receive one set of wheels and guide the plate in its operative movement and maintain it in its chosen position. In conjunction with the race assembly, the adjustable stops 20 are provided for. Where it may be found desirable or necessary, a race assembly may be employed for each set of wheels, the race assembly or assemblies may be adjustably mounted to provide adjustment in a line perpendicular to the race way, and the stops 20 may be located on any appropriate part of the bench rather than being associated with the race assembly.

With the apparatus suitably mounted on the machine bench, its operation is as follows: The material or garment upon which the row of buttonholes is to be made or buttons are to be affixed as indicated by numeral 40, is clamped into position by clamps 12, with the portion of the garment to be operated on being located over the cut out area 11. Any number of such clamps as are found necessary being employed. The clamps having been fixed in adjusted position in their slots for the particular run of work to be done, the garment is brought into proper position by having its edge run against the guide flanges 30 of the clamps, to fix the distance of the buttons or buttonholes from the edge of the garment. The portion of the garment upon which it is desired that the machine operate is now properly located over the cut out portion 11. The stops 20 are then spaced from each other the distance desired between the buttons or buttonholes. With the plate brought into engagement with the first stop, the point on the garment to receive the first buttonhole or button is positioned at the operating point of the machine. With the garment thus positioned and the stops properly adjusted, the button or buttonhole machine is operated. The plate is then moved to the next stop, where the operation is repeated, and so on until the desired number of buttonholes have been cut or buttons affixed.

It is understood that this disclosure describes only the preferred embodiment of the invention,

and modification of its structure within the spirit and scope of this invention will be apparent to those skilled in the art.

What is claimed is:

5. A device of the character described comprising a garment carrying plate and a race assembly; said plate having a cut-out operating area and elongated transverse slots; clamps adjustably secured to said plate through said slots, and located on opposite sides of the operating area, the adjustability of said clamps being transverse to the race, two sets of wheels depending from the plate, one set of wheels positioned in said race assembly, a yieldable catch depending from said plate, and adjustable stops positioned along the race assembly; the race assembly cooperating with said wheels to guide the plate in its movement therealong, said catch cooperating with said stops to arrest the movement of said plate along the race assembly at a plurality of predetermined points.
10. 2. A device of the character described comprising a garment carrying plate and a race assembly; said plate having a cut-out operating area, a plurality of clamps adjustably secured thereto, wheels depending therefrom, and a yieldable catch depending therefrom; said race assembly having a plurality of adjustable stops located therealong; said wheels cooperating with said race assembly to guide the plate in its movement therealong, said catch cooperating with said stops to arrest the movement of said plate along the race assembly at a plurality of predetermined points.
15. 3. A device of the character described comprising a garment supporting plate, a race assembly, and stops; said plate having a cut-out operating area, clamps adjustably secured thereto, wheels depending therefrom, and a catch secured thereto; said wheels cooperating with said race assembly to guide said plate in its movement therealong, and said catch cooperating with said stops to arrest the movement of said plate along the race assembly at a plurality of predetermined points.
20. 4. In combination: a buttonholing or button sewing machine, a bench supporting the machine, and a device mounted on said bench for positioning and spacing a series of buttonholes in 40 or buttons on a garment; said device comprising a garment carrying plate and a race assembly; said plate having a cut-away operating area and elongated transverse slots; clamps adjustably secured to said plate through said slots, and located 45 on opposite sides of the operating area, the adjustability of said clamps being transverse to the race, two sets of wheels depending from the plate, one set of wheels positioned in said race assembly, a yieldable catch depending from said plate, and adjustable stops positioned along the race assembly; said device operating to carry and move a garment into several positions with respect to said machine for accomplishing a predetermined positioning and spacing of the buttonholes or buttons.
50. 5. In combination, a machine for working upon a garment at predetermined, aligned, and spaced points, a bench supporting the machine, a device adapted to carry and move the garment into the several positions for the above operations; said device comprising a garment carrying plate and a race assembly; said plate having an operating area cut away therefrom, a plurality of clamps adjustably secured thereto, wheels depending therefrom, and a yieldable catch depending there-
55. 70. 75.

from; said race assembly having a plurality of adjustable stops located therealong; said wheels cooperating with said race assembly to guide the plate in its movement therealong, said catch cooperating with said stops to arrest the movement of said plate along the race assembly at a plurality of predetermined points.

6. In combination, a machine for working upon a garment at predetermined, aligned, and spaced points, a bench supporting the machine, a device adopted to carry and move the garment into the several positions for the above operations; said device comprising a garment supporting plate, a race assembly, and stops; said plate having an operating area cut away therefrom, clamps adjustably secured thereto, wheels depending therefrom, and a catch secured thereto; said wheels cooperating with said race assembly to guide said plate in its movement therealong

and said catch cooperating with said stops to arrest the movement of said plate along said race assembly at a plurality of predetermined points.
